Des. 222,633
Patented Nov. 23, 1971

222,633

COMBINED STORAGE AND DISPLAY CART

Robert W. Carter and Walter P. Graber, Cadillac, Mich.,
assignors to Kysor Industrial Corporation, Cadillac,
Mich.

Filed Nov. 10, 1969, Ser. No. 20,004

Term of patent 14 years

Int. Cl. D12—02; D6—04
U.S. Cl. D14—3

FIG. 4

FIG. 5

FIG. 1 is a perspective view of a combined storage and display cart embodying our new design, one castor being broken away for convenience of illustration;

FIG. 2 is an elevational view taken from one end thereof, the opposite end being the same as the end shown;

FIG. 3 is an elevational view taken from one side thereof, the opposite side being the same as the side shown;

FIG. 4 is a top plan view thereof; and

FIG. 5 is a bottom view thereof.

We claim:

The ornamental design for a combined storage and display cart, substantially as shown and described.
